(57) CLAIM

The ornamental design for a “paintbrush holder,” as shown and described.

DESCRIPTION

FIG. 1 is a front elevational view of a “paintbrush holder” showing my new design;

FIG. 2 is a rear elevational view thereof;

FIG. 3 is a top plan view thereof;

FIG. 4 is a bottom plan view thereof;

FIG. 5 is a left side elevational view thereof, the right side being the mirror image thereof;

FIG. 6 is a top left side perspective view thereof; and,

FIG. 7 is a top left side perspective view similar to FIG. 6 showing the “paintbrush holder” in use.

The material shown in phantom in FIG. 7 is for illustration purposes only and does not form a part of the design.
